UNITED STATES PATENT OFFICE

156,989

PUPPET HEAD OR SIMILAR ARTICLE

Frank Paris, New York, N. Y.

Application April 28, 1948, Serial No. 146,002

Term of patent 3½ years

(Cl. D34—4)

To all whom it may concern:

Be it known that I, Frank Paris, a citizen of the United States, residing at New York, in the county of New York and State of New York, have invented a new, original, and ornamental Design for a Puppet Head or Similar Article, of which the following is a specification, reference being had to the accompanying drawing, forming part thereof.

Fig. 1 is a front view of a puppet head or similar article, showing my new design.

Fig. 2 is a side view of the puppet head or similar article shown in Fig. 1.

I claim:
The ornamental design for a puppet head or similar article, substantially as shown.

FRANK PARIS.
